DESIGN FOR A MECHANICAL PENCIL OR SIMILAR ARTICLE

Lawrence Wilson Saulsbury, Valley Stream,
N. Y., assignor to Eagle Pencil Company, New
York, N. Y., a corporation of Delaware

Application March 29, 1940, Serial No. 91,337

Term of patent 7 years

To all whom it may concern:

Be it known that I, Lawrence Wilson Saulsbury, a citizen of the United States and residing at Valley Stream, New York, have invented a new, original, and ornamental Design for a Mechanical Pencil or Similar Article, of which the following is a specification, reference being had to the accompanying drawing, forming part thereof, and in which

Fig. 1 is a side elevational view of a mechanical pencil, showing my new design, and

Fig. 2 is a development of the barrel of the mechanical pencil, but shown on a somewhat enlarged scale.

The dominant features of my design reside in the parts shown in full lines.

I claim:

The ornamental design for a mechanical pencil or similar article, substantially as shown and described.

LAWRENCE WILSON SAULSBURY.
